PERCY H. THOMAS, OF UPPER MONTCLAIR, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,193,083.

Specification of Letters Patent.

Patented Aug. 1, 1916.

Continuation of application Serial No. 774,810, filed June 20, 1913. This application filed March 6, 1916.
Serial No. 82,327.

To all whom it may concern:

Be it known that I, PERCY H. THOMAS, a citizen of the United States, residing at Upper Montclair, in the county of Essex and State of New Jersey, have invented certain new and useful Improvements in Railway Signaling, of which the following is a specification.

My invention relates to signaling for electric railways, and to relays adapted particularly for use in such systems.

The present application is a continuation of my co-pending application filed June 20, 1913, Serial No. 774,810, for railway signaling.

I will describe one form of railway signaling system embodying my invention, and will then point out the novel features thereof in claims.

20 The accompanying drawing is a view showing diagrammatically one form of railway signaling and one form of relay embodying my invention.

Referring to the drawing, 1 and 2 designate the track rails of a railway track, which track is divided into a plurality of successive block sections A, B, etc. As here shown, the limits of these block sections are determined by insulated joints 10 in both of the 30 lines of track rails, although it is understood that the limits of the block sections may be defined in other ways.

The normal direction of movement of cars or trains along the railway is in the direction indicated by the arrow. Traffic through 35 block section A is governed by a signal S^A, and traffic through block section B is governed by a signal S^B; these signals are controlled by relays R, as hereinafter explained.

40 G designates a generator of alternating current for furnishing energy for the propulsion of cars or trains along the railway. One terminal of this generator is connected with a third rail or trolley 11, extending 45 along the railway, and the other terminal is connected with the track rails of the railway; as here shown, the last-mentioned terminal of the generator G is connected with the middle point of an inductive bond 13, 50 the two terminals of which are connected respectively with the two track rails. The purpose of this bond 13 is, as usual, to avoid

short-circuiting the track rails at the points of connection of the generator G with these rails.

55 In the form of railway here shown, both track rails are included in the circuit for the propulsion current, hence I provide adjacent the ends of each block section inductive bonds 12 of a usual and well known type for 60 the purpose of conducting the propulsion current from the track rails of the adjacent block sections. Each of these bonds 12 comprises as usual a core of magnetic material provided with a winding 12^a, the terminals 65 of the winding being connected with the track rails respectively, and the middle point of the winding of each bond being connected with the middle point of the winding of adjacent bond for the adjacent 70 block section. The operation of these inductive bonds 12 is so well known that no explanation is required herein.

G' is a generator of alternating signaling current, the current from which differs in 75 frequency from the current delivered by the propulsion generator G. For example, the frequency of the propulsion current from generator G may be 25 cycles per second, while the frequency of the signaling current 80 from the generator G' may be 60 cycles per second; for purposes of this specification I will assume these two frequencies for the two currents, although it is understood that other frequencies may equally well be employed. The terminals of the generator G' are connected with transmission mains 14 which extend along the railway.

85 Each block section A, B, etc., is provided with a track circuit comprising as usual the 90 two track rails of the section, a source of signaling current, and the relay R. As here shown, the source of signaling current for each track circuit is the generator G', a transformer T being interposed between 95 the mains 14 and the track rails of each block section.

100 Each relay R in the form here shown comprises a movable member 15 mounted to oscillate on a sharp-edged support 16. The member 15 is provided with three arms 15^a, 15^b, and 15^c, the angle between arms 15^a and 15^b being considerably less than 180°. The arm 15^c is provided with a contact plate

20 which is adapted to engage with a spring contact finger 21. The member 15 is capable of assuming a middle position (the position in which member 15 of relay R for block 5 section B is shown in the drawing) in which position contact 20—21 is closed, and is capable of rocking in either direction from the middle position to engagement with a stop 22 or a stop 27, in either of which 10 positions the contact 20—21 is opened. The member 15 is biased by a torque to such position that it engages with stop 22; as here shown this bias is effected by a counterweight comprising a screw 28 fixed in one 15 arm of the member and a nut 29 adapted to work on the screw. Two other torques are exerted on member 15 by currents in two windings 25 and 26; one of these torques increases with increase of frequency and the 20 other decreases with increase of frequency, and the difference between these torques at a selected frequency is equal and opposite to the torque exerted by the counterweight 28. As here shown, each winding 25, 26 is in 25 the form of a solenoid and is provided with a longitudinally movable core 23 or 24 of magnetic material. Each core 23, 24 is operatively connected with the member 15 by a cord 33 or 35, which cords are held in suitable grooves formed in the extremities of 30 arms 15^a and 15^b respectively.

With the construction just described, it will be seen that if the torques exerted on the member 15 by the action of cores 23 and 35 24 are equal, with member 15 in its middle position they will neutralize each other and the member 15 will be drawn toward and held against the stop 22 by the counterweight 28, 29, so that contact 20—21 will be 40 open; if the difference between the torques produced by cores 24 and 23 with member 15 in its middle position is equal and opposite to the torque produced by the counterweight 28, 29, the member 15 will be drawn 45 to and held in the middle position, because in any other position one of the effective lever arms 15^a or 15^b would be greater than it is in the middle position and the other will be less than in the middle position 50 (owing to the fact that arms 15^a and 15^b are less than 180° apart) and consequently the difference between the torques produced by the windings would no longer neutralize the torque produced by the counterweight: 55 contact 20, 21 is then closed; and if the relation of the torque produced by cores 23 and 24 is any other than that last specified, the member 15 will be drawn toward and held against one or the other of stops 22 60 or 27, so that contact 20, 21 is open. In the specific embodiment of my invention shown herein, the length of arm 15^b is greater than that of arm 15^a by an amount such that when the forces are exerted on these arms by 65 cores 23 and 24 are equal, the difference be-

tween the torques produced by cores 24 and 23 with member 15 in the middle position is equal and opposite to the torque produced by counterweight 28, 29.

The windings 25 and 26 are connected in 70 multiple across the track rails 1 and 2; included in series with winding 25 is a reactance 30, and included in series with winding 26 is a condenser 31. The circuit for these windings is from track rail 1 through 75 wire 32, then through the multiple circuit, one branch of which includes winding 25 and reactance 30, and the other branch of which includes the winding 26 and the condenser 31, then through wire 34 to track 80 rail 2. In the specific embodiment of my invention shown herein, the multiple circuits of the windings 25 and 26 are so adjusted that when current of the signaling frequency flows in these windings, the forces 85 exerted on the cores 23 and 24 are equal, hence at any other frequency the forces exerted on these cores are unequal; this adjustment may be accomplished by providing the same number of turns in the windings 90 25 and 26 and so adjusting the circuits that the currents in these windings are equal at the signaling frequency and unequal at any other frequency, or it may be accomplished by providing the windings 25 and 95 26 with different numbers of turns and so adjusting the circuits that at the signaling frequency the currents in the two windings are inversely proportional to the number of turns. In the drawing I have indicated the 100 former method of obtaining the desired adjustment, by indicating that the number of turns in the two windings 25 and 26 are equal.

It will be seen from the foregoing that I 105 provide means for exerting on the member 15 opposing torques one of which increases with increase of frequency and the other of which decreases with increase of frequency, and means for exerting a third constant 110 torque independent of frequency for balancing the difference between the other two torques at a selected frequency.

Each signal S^A, S^B, etc., is provided with a controlling circuit, which circuit is controlled by contact 20—21 of the corresponding relay. The circuit for signal S^B is from battery 36 through contact 20—21, signal S^B, to battery 36. The circuit for signal S^A is similar.

The operation of the signaling system shown herein is as follows: When a block section is unoccupied, as block section B in the drawing, the windings 25 and 26 of relay R for such block section are energized 125 by signaling current from transformer T of that block section, so that contact 20—21 of that relay is closed, and signal S^B, therefore, indicates clear. When, however, a block section is occupied by a car or train W, 130

as block section A, the wheels and axles of such car or train shunt the signaling current from relay R of that block section, so that contact 20-21 of that relay is held open by counterweight 28, 29, and signal S^A, therefore, indicates stop.

If, while car or train W occupies block section A, the potential of the propulsion current in rails 1 and 2 of this block section should be different, propulsion current would flow through the windings 25 and 26 of relay R of this block section. Since, however, the frequency of the propulsion current is 25 cycles, the value of this current in winding 25 would be greater than the value of this current in winding 26 (because as the frequency decreases the current increases through reactance 30 and decreases through condenser 31 for given potential) hence, the torque produced on member 15 by core 23 would exceed that produced by core 24, and the propulsion current would, therefore, assist the counterweight 28, 29 to hold contact 20-21 open.

In case an alternating current of a frequency higher than 60 cycles should reach the windings 25 and 26, the current in winding 26 would be greater than at 60 cycles (for a given potential) and the current in winding 25 would be less than at 60 cycles (for a given potential), hence, the force produced by winding 26 would be greater than that produced by winding 25 at any voltage, and unless the voltage were at the critical point where the difference of torque, with member 15 in its middle position is just sufficient to balance the torque of the counterweight, the member 15 would be drawn toward and held against stop 27 so that contact 20-21 would be held open.

It will be seen from the foregoing that I have provided a relay which is responsive to alternating current of one frequency to close its contacts, but is not responsive to alternating current of any other frequency, either higher or lower, to close its contacts.

Although I have herein shown and described only one form of relay and only one form of railway signaling embodying my invention, it is understood that various changes and modifications may be made therein within the scope of the appended claims without departing from the spirit and scope of my invention.

Having thus described my invention, what I claim is:

1. In combination, an electric railway the track rails of which are included in the circuit of the propulsion current; a source of alternating propulsion current; a source of alternating signaling current connected with the track rails and differing from the propulsion current in frequency; a relay comprising a movable member, two windings connected with the track rails and

adapted to exert torque in opposite directions on said member; means associated with said windings for causing the torques to vary at different rates with variations of frequency, means for exerting on said member a third torque independent of frequency for balancing the difference between the two first-mentioned torques at the frequency of the signaling current; a signal, a controlling circuit for said signal, and means controlled by said movable member for closing said circuit when the torques on the member are balanced but not when the torques are unbalanced in either direction.

2. In combination, an electric railway the track rails of which are included in the circuit of the propulsion current; a source of alternating propulsion current, a source of alternating signaling current connected with the track rails and differing in frequency from the propulsion current; a relay comprising a movable member having a middle position and capable of movement in opposite directions from said middle position, means for biasing said member in one direction from said middle position, two windings connected in multiple across the track rails and adapted to exert torque on the said member in opposite directions, means included in circuit with said windings for causing the currents therein to vary at different rates with changes in frequency, the circuits of the windings and their lever arms being so proportioned that at the frequency of the signaling current the difference between the torques produced by the said windings is equal to and opposite to the torque produced by the biasing means, whereby at the signaling current frequency the member occupies its middle position and

whereby at any other frequency the member is moved in one direction or the other from the middle position; a railway signal; a controlling circuit for said signal, and means operated by said movable member for closing said circuit when the member occupies its middle position and for opening said circuit when the member is moved in either direction from said middle position.

3. In combination, an electric railway the track rails of which are included in the circuit of the propulsion current; a source of alternating propulsion current, a source of alternating signaling current connected with the track rails and differing in frequency from the propulsion current; a relay comprising a movable member having a middle position and capable of movement in opposite directions from said middle position, means for biasing said member in one direction from said middle position, two windings connected in multiple across the track rails and adapted to produce torque on the said member in opposite directions, the lever

arms of said windings being such that when the forces exerted by the two windings are equal the difference between the torques produced by the windings is equal to and 5 opposite to the torque produced by the biasing means, means included in the circuits of said windings for causing the currents therein to vary at different rates with changes in frequency, the circuits being so 10 proportioned that at the signaling current frequency the forces exerted by the two windings are equal, whereby at the signaling current frequency the member occupies its middle position and whereby at any 15 other frequency the member is moved in one direction or the other from the middle position; a railway signal; a controlling circuit for said signal, and means operated by said movable member for closing said circuit when the member occupies its middle position 20 and for opening said circuit when the member is moved in either direction from said middle position.

4. In combination, an electric railway the 25 track rails of which are included in the circuit of the propulsion current, a source of alternating propulsion current, a source of alternating signaling current connected with the track rails and differing in frequency 30 from the propulsion current; a relay comprising a movable member having a middle position and capable of movement in opposite directions from said middle position, means for biasing said member in one direction from said middle position, two windings having equal numbers of turns connected in multiple across the track rails and adapted to produce torque on the said member in opposite directions, the lever arms of 35 the torques produced by said windings being such that when the forces exerted by the windings are equal the difference between the torques produced by the windings is equal to and opposite to the torque of the 40 biasing means, means included in the circuits of the windings for causing the currents in the windings to be equal at the signaling frequency and unequal at all other frequencies, whereby at the signaling current 45 frequency the member occupies its middle position and whereby at any other frequency the member is moved in one direction or the other from the middle position; a railway signal; a controlling circuit for 50 said signal, and means operated by said movable member for closing said circuit when the member occupies its middle position and for opening said circuit when the member is moved in either direction from said middle 55 position.

5. In combination, an electric railway the track rails of which are included in the circuit of the propulsion current, a source of alternating propulsion current, a source of 60 alternating signaling current differing in

frequency from the propulsion current; a relay comprising a movable member having a middle position and capable of oscillation in both directions from said middle position, means for biasing said member in one direction from said middle position, said member having two lever arms forming an angle of less than one hundred eighty degrees, two magnetic cores acting respectively on said lever arms, two windings connected in multiple across the track rails and acting respectively on said lever arms, means included in circuit with said windings for causing the currents therein to vary at different rates with changes in frequency, the 75 circuits of the windings and the said lever arms being so proportioned that at the frequency of the signaling current the difference between the torques produced on the movable member by the said cores is equal 80 and opposite to the torque produced by the said biasing means, whereby at the signaling current frequency the member occupies its middle position and whereby at any other frequency the member is moved in one direction 85 or the other from the middle position; a railway signal; a controlling circuit for said signal, and means operated by said movable member for closing said circuit when the member occupies its middle position and for opening said circuit when the member is moved in either direction from 90 said middle position.

6. In combination, an electric railway the track rails of which are included in the circuit of the propulsion current, a source of alternating propulsion current, a source of alternating signaling current connected with the track rails and differing from the propulsion current in frequency; a relay comprising a movable member, two windings connected with the track rails and adapted to exert torques in opposite directions on said member, means associated with said windings for causing the torque exerted by 105 one winding to increase with increase of frequency and the torque exerted by the other winding to decrease with increase of frequency, means for exerting on said member a third torque independent of frequency for 110 balancing the difference between the two first-mentioned torques at the frequency of the signaling current; a railway signal, a circuit for the control of said signal, and means controlled by said movable member 115 for closing said circuit when the torques on said member are balanced and for opening said circuit when the torques on said member are unbalanced in either direction.

7. An electric relay comprising a movable 125 member, means for exerting on said member a torque which increases with increase of frequency, means for exerting on said member an opposing torque which decreases with increase of frequency, means for exert- 130

ing on said member a third torque independent of frequency for balancing the difference between the two first-mentioned torques at a selected frequency, and means controlled by said member for closing an electric circuit when the torques are balanced and for opening the circuit when the torques are unbalanced in either direction.

8. A relay comprising a movable member, two windings adapted to exert torques on said member in opposite directions, means associated with said windings for causing the torque exerted by one winding to increase with increase of frequency and the torque exerted by the other winding to decrease with increase of frequency, means for exerting on said member a third torque independent of frequency for balancing the difference between the two first-mentioned torques at a selected frequency, and means controlled by said member for closing an electric circuit when the torques are balanced and for opening the circuit when the torques are unbalanced in either direction.

9. A relay comprising a movable member, two windings adapted to exert torques on said member in opposite directions, means associated with said windings for causing the torques exerted thereby to vary at different rates with variations in frequency, means for exerting on said member a third torque independent of frequency for balancing the difference between the two first-mentioned torques at a selected frequency, and means controlled by said member for closing an electric circuit when the torques are balanced and for opening the circuit when the torques are unbalanced in either direction.

10. A relay comprising a movable member, two windings adapted to exert torque on said member in opposite directions, the effective lever arms of said torques being different, means associated with said windings for causing the forces exerted on said member by the windings to be equal at a selected frequency and to vary at different rates with variations of frequency, and means for exerting on said member a third torque independent of frequency for balancing the difference between the two first-mentioned torques when the forces exerted by said windings are equal.

11. A relay comprising a movable member, two windings adapted to exert torque on said member in opposite directions, the effective lever arms of said torques being different, means associated with said windings for causing the forces exerted on said member by the windings to bear a predetermined relation at a selected frequency and to vary at different rates with variations of frequency, and means for exerting on said member a third torque independent of frequency for balancing the difference between

the two first-mentioned torques when the forces exerted by said windings bear the said predetermined relation.

12. A relay comprising a movable member, two windings having equal numbers of turns adapted to exert forces on said member tending to rotate the member in opposite directions, the effective lever arms at which said forces are exerted being different, means associated with said windings for causing the currents in said windings to be equal at one frequency and to vary at different rates with variations of frequency, and means for exerting on said member a force independent of frequency for balancing the two first-mentioned forces when the currents in the two windings are equal.

13. A relay comprising a movable member having two lever arms disposed at an angle of less than one hundred eighty degrees, two windings acting respectively on said lever arms to produce torques on said member in opposite directions, means associated with said windings for causing the torques exerted thereby on the member to vary at different rates with variations of frequency, and means for exerting on said member a third torque independent of frequency for balancing the difference between the two first-mentioned torques at a selected frequency.

14. A relay comprising a member movable in opposite directions from an intermediate position, means for exerting thereon two opposing torques which vary at different rates with variations of frequency, and means for exerting on said member a third torque independent of frequency for balancing the difference between the two first-mentioned torques at a selected frequency when the member occupies the said intermediate position but not when the member is on either side of said intermediate position.

15. A relay comprising a member movable in opposite directions from an intermediate position, means for exerting on said member two opposing torques which vary at different rates with variations of frequency, the structure being such that the effective length of the lever arm for each torque decreases when the member moves from the intermediate position in the direction of the force acting on that lever arm and increases when the member moves in the opposite direction from its intermediate position, and means for exerting on said member a third torque independent of frequency for balancing the difference between the two first-mentioned torques at a selected frequency when the member occupies its intermediate position but not when the member is on either side of said intermediate position.

16. A relay comprising a movable member, two windings adapted to exert torques

- 6
- on said member in opposite directions, an inductive reactance in series with one winding and a capacity reactance in series with the other winding whereby the torque exerted by the first-mentioned winding decreases with increase of frequency and the torque exerted by the second winding increases with increase of frequency, means for exerting on said member a torque independent of frequency for balancing the difference between the two first-mentioned torques at a selected frequency, and means controlled by said member for closing an electric circuit when the torques on the member are balanced and for opening the circuit when the torques are unbalanced in either direction.
17. A relay comprising a member movable in opposite directions from an intermediate position, means for exerting on said member a torque which increases with increase of frequency, means for exerting on said member an opposing torque which decreases with increase of frequency, means for exerting on said member a third torque independent of frequency for balancing the difference between the two first-mentioned torques at a selected frequency, and a contact closed when the member occupies the said intermediate position and opened when the member moves in either direction from said intermediate position.
18. In combination, an alternating current electric railway the track rails of which are included in the circuit for the propulsion current, a source of alternating signaling current connected with the track rails and differing from the propulsion current in frequency, a relay connected with the track rails and responsive to current of the signaling frequency but not to current substantially higher or substantially lower than the signaling current in frequency, and a signal controlled by said relay.
19. In combination with the track rails of a railway, a source of alternating signaling current connected therewith, a relay also connected with said track rails and responsive to current of the signaling frequency but not to current substantially higher or substantially lower than the signaling current in frequency, and a signal controlled by said relay.
20. In combination with the track rails of a railway, means for supplying alternating signaling current thereto, a relay responsive to current of the signaling frequency but not to current substantially higher or substantially lower than the signaling current in frequency, means for energizing said relay from the track rails, and a signal controlled by said relay.
21. In combination with the track rails of a railway, means for supplying alternating signaling current thereto; a relay comprising a movable member, two windings connected with the track rails and adapted to exert torques on said member in opposite directions, means for causing one of said torques to vary directly and the other inversely with variations of frequency of the current in the track rails, means for exerting on said member a third torque independent of frequency for balancing the difference between the two first-mentioned torques at the frequency of the signaling current, a signal, a circuit therefor, and means controlled by said movable member for closing said circuit when the torques on the member are balanced but not when the torques are unbalanced in either direction.

In testimony whereof I affix my signature in presence of two witnesses.

PERCY H. THOMAS.
